STRIPPING MACHINE

Bernard M. Packtor, Springfield, Mass.

Application September 25, 1943, Serial No. 503,835

3 Claims. (Cl. 164—65)

(Granted under the act of March 3, 1883, as
amended April 30, 1928; 370 O. G. 757)

The invention described herein may be manufactured and used by or for the Government for governmental purposes without the payment to me of any royalty thereon.

This invention relates to a machine for automatically stripping and coiling strips of various widths of sheet material from a single roll.

In the woodworking industry where considerable sanding is utilized to produce a finish on the manufactured product, long sanding belts are frequently used. These sanding belts generally are cut from a comparatively wide roll of sanding cloth. Such sanding cloth taken directly from the roll could not of course be utilized directly because of its great width. It is therefore necessary to manually cut from this roll the width and length of sanding belt desired. When such strips are manually cut from the roll by using hand shears, for example, considerable expenditure in time and effort is consequently necessary. In any other industry using rolls of sheetlike, fibrous base material a similar cutting problem exists.

While some form of cutting equipment or device has been employed in the past such devices usually utilized knives or other cutters. Particularly when cutting sandpaper the abrasive surface of the sanding cloth soon dulled such cutters or knives requiring frequent resharpening of the blades.

Accordingly an object of this invention is to provide a machine for automatically stripping and coiling a plurality of single rolls of sheet material from a single wide roll.

A particular object of this invention is to provide a sanding cloth stripping machine for stripping variable widths of sanding cloth from a roll without the use of knives or other cutters.

Still another object of this invention is to provide an automatic sheet material stripping machine having readily removable and replaceable spools for storing the narrow width material so stripped from a single wide roll.

The specific nature of the invention as well as other objects and advantages thereof will clearly appear from a description of a preferred embodiment as shown in the accompanying drawings in which:

Fig. 1 is a front elevational view of the stripping machine.

Fig. 2 is a right side elevational view of Fig. 1.

Fig. 3 is an enlarged detail view in longitudinal section showing the manner of mounting the spindle with respect to the driving gear.

Fig. 4 is a detail view of the splined bearing and splined bearing clamps.

The automatic stripping machine operates on the principle that the sheet material, particularly sanding cloth, will tear in a straight line along the length of the belt. This invention, to be described in more detail later, comprises an arrangement whereby the roll of sheet material, of which sanding cloth will be used as an example, is mounted above two horizontal spindles. An idler roller is mounted horizontally midway between the two spindles. A suitable gear connection between the two spindles is provided and motion is imparted to this gearing by a hand crank. The roll of sanding cloth is then divided into the width of strips desired and where such divisions are marked short tears are started in the sanding cloth either manually or by a knife operatively mounted on the machine and preferably transversely adjustable with respect to the sanding cloth. The two horizontal spindles previously mentioned hold spools on which the strips of sanding cloth are to be wound. The strips of sanding cloth are first led around the idler roller, alternate strips then being secured first to a spool on the upper spindle, then to a spool on the lower spindle. This is repeated until all the strips are secured to the remaining spools on the upper and lower spindles. By turning the crank the spindles may then be readily revolved and the wide roll of sanding cloth will be quickly separated into a number of smaller strips. Due to the large angular displacement between the strips on the upper and lower spindles the cloth will be readily separated by tearing.

Referring to the figures wherein like characters refer to similar parts there are provided brackets 1 and 2 which are substantially rectangular plates. The brackets 1 and 2 are secured to vertical uprights 3 by the bolts 4, Fig. 2. The uprights may be any suitable length of channel iron or angle iron and are securely bolted to a wall or a substantial bracket. A spindle 5 is mounted in semi-circular notches 6 provided in the top of each bracket 1 and 2 and is retained therein by split bearings 7.

Each split bearing 7 is a thin semi-cylindrical member provided with two integral oppositely disposed lugs 8. A corresponding semi-circular notch 9 similar to notch 6 is provided on the underside of each split bearing 7 to accommodate the spindle 5. Small U-shaped clamps 9' are pivotally mounted on brackets 1 and 2 by a pin 10 directly under the lugs 8. A thumb screw 11 provided in the top of each clamp 9' secures split bearings 7 to the top of brackets 1 and 2. A roll 12 of the material to be stripped is mounted on

spindle 5 by means of conical hubs 13 inserted in each end of roll 12. If desired, a suitable friction device 14 which comprises a flat spring member may be suitably secured to bracket 2 to frictionally engage the hubs 13 on the left side of spindle 5. Friction device 14 is provided to prevent the roll 12 from uncoiling too freely due to its inertia.

Spindles 15 and 16 are mounted in suitable holes near the forward edge of brackets 1 and 2, the spindle 15 being placed a short distance below spindle 5 and spindle 16 being placed near the bottom of brackets 1 and 2. The central portion of each spindle 15 and 16 is of square cross section as shown in Fig. 2. Adjacent the square portion on each spindle 15 and 16 a short cylindrical end portion is provided. The right end of each spindle 15 and 16 as viewed in Fig. 1 is threaded to receive a nut 19. Spools 20 are mounted on the square portion 17 of spindle 15 and are separated by spacers 21. A large washer 22 is placed adjacent the outside faces of the first and last spools placed on spindle 15. A collar 23 is secured to the left end of spindle 15 (Fig. 1) by a screw 24. The spacers 21 and spools 20 are retained on spindle 15 by the nut 19. Spools 27 are mounted on spindle 16 in a manner similar to the mounting of spools 20 on spindle 15 except that spools 27 are mounted opposite spacers 21 on spindle 15. Slots 20a and 27a are respectively provided in the hubs of spools 20 and 27.

The ring hand ends of spindles 15 and 16 are provided with transverse U-shaped notches 25 for a purpose to be described. If desired a spring 26 may be mounted on the left end of spindles 15 and 16 between the brackets 2 and collar 23 to bias the spindles 15 and 16 against the inside face of bracket 1. Sufficient clearance is maintained between the inside face of bracket 2 and the adjacent spool 20 so that spindles 15 and 16 may be readily pushed to the left as viewed in Fig. 1 to disengage the right end from bracket 1 in order that spindles 15 and 16 may be quickly removed.

To provide additional support for brackets 1 and 2 two tie rods 29 are provided near the forward edges of brackets 1 and 2 at the top and bottom thereof. The tie rods are secured to brackets 1 and 2 by nuts 30. A rectangular bracket 31 is perpendicularly mounted on the outside face of bracket 1 and suitably secured thereto as by welding. Bracket 31 is placed near the top of bracket 1 and flush with the forward face thereof. Another similar bracket 32 is mounted in like fashion near the bottom of bracket 1. A plate 33 is secured to brackets 31 and 32 by the screws 34. Two short shafts 37 are provided opposite spindles 15 and 16 for mounting identical gears 35. Adjacent ends of shafts 37 are supported by plate 33. Suitable axial holes are provided in the hubs 36 of gears 35 for mounting the gears on the ends of spindles 15 and 16 and on shafts 37. Gears 35 are secured to their respective shafts 37 by set screws 40.

Transverse pins 38 passing thru the hub 36 engage the U-shaped notches 25 in the end of spindles 15 and 16 respectively so that gears 35 will drive each spindle 15 and 16. A collar 38' is placed on shafts 37 adjacent the outside face of plate 33 and is secured to the shafts by a screw 39 in the collar 38'. A driving gear 41 is mounted between the bracket 1 and plate 33 on a shaft 42 and engages both the gears 35. A set screw 43 in the hub of gear 41 secures gear 41 to shaft 42. A crank 44 is suitably secured to an outwardly

projecting end of shaft 42 for the purpose of driving gear 41 which in turn drives the gears 35.

5 A feeding roller 45 is mounted on a shaft 46, which is in turn supported by the brackets 1 and 2 midway between the spindles 15 and 16 and with its rear periphery substantially aligned with the rear of roll 12.

A triangular bracket 47 is secured to the forward edge of each bracket 1 and 2 as shown in Fig. 2 by screws 48. Brackets 47 are mounted somewhat above the center of gear 41. A horizontal table 49 is placed across the brackets 47 and is secured to brackets 47, preferably by welding. A horizontal rod 50 is mounted between brackets 1 and 2 directly in back of table 49 and is secured to brackets 1 and 2 by the nuts 51. A cutter 52 is slidably mounted on rod 50. Cutter 52 comprises a short rectangular member having an enlarged circular end 53 in which is provided an axial hole for mounting on the rod 50. A beveled edge 54 is provided on each side of cutter 52 and these afford sharp shearing edges for starting tears in the material on roll 12 in a manner to be described.

25 A roll 12, for example of sanding cloth, may be conveniently placed on spindle 5 by unloosening screws 11 of clamps 9' and removing split bearings 7. Spindle 5 is then inserted thru the hubs 13 of roll 12 and the spindle and roll replaced in the bearing notches 6 in brackets 1 and 2. Split bearings 7 are then replaced and clamps 9' pivoted over the lugs 8 and thumb screws 11 tightened to secure the split bearings 7 to the brackets 1 and 2. The sheet of sanding cloth from roll 12 is then led around roller 45 and up on the table 49. The sanding cloth is then divided into suitable widths of strips which spools 20 and 27 will accommodate. The beveled edges 54 of cutter 52 are then successively placed on each of the markings made on the sanding cloth and short tears are started on the edge of the cloth. It should be mentioned here that suitable graduations (not shown) may be engraved on the surface of plate 49 to facilitate subdividing the sanding cloth into strips of desired widths.

50 Starting from right to left as viewed in Fig. 1 the first strip of sanding cloth started by tearing is brought up to first spool 20 on spindle 15 and inserted in a slot 20a in the hub thereof. The following adjacent strip is then brought downwardly and inserted in a slot 27a in the first spool 27 which lies directly under the first spacer 21 on the spindle 15. The remaining strips are 55 similarly successively secured to the other spools on spindles 15 and 16. When crank 44 is turned, causing spindles 15 and 16 to revolve, the sanding cloth is automatically stripped and coiled onto the individual spools on spindles 15 and 16.

60 The broken line 55 (Fig. 2) representing the sheet of sanding cloth being uncoiled from a full roll of sanding cloth indicates, after passing the roller 45 the angular displacement of a strip of sanding cloth being wound on one of the spools 20 on the upper spindle 15 and on one of the spools 27 of spindle 16. The angle between adjacent strips is preferably about 90°. It is this large angular displacement between the two adjacent strips of sanding cloth that enables the device herein described to accurately tear the large roll into small strips. It is readily apparent that a great variety of combinations of variable widths of sanding cloth may be stripped from a single wide roll by merely replacing the spools 20 and 27 with spools of varying widths. It is also

desired to point out that in place of crank 44 a pulley or gear (not shown) may be attached to shaft 42 and the device driven by power.

It should be distinctly understood that the described application of the machine to the stripping of sanding cloth represents only one particularly desirable application and that the machine may be utilized to strip any sheetlike material capable of tearing in a straight line.

I claim:

1. In an apparatus for tearing and coiling sheet material, means arranged to rotatably support a roll of sheet material, a table arranged to receive the end portion of said sheet material, a cutter mounted for transverse movement across said table whereby the end portion of the sheet material may be cut into a plurality of strips, a plurality of spaced, rotatably mounted spindles, means on each of said spindles for respectively engaging successive strips of said material, and means for simultaneously rotating said spindles whereby the sheet material is torn into lengthwise strips and the strips coiled on the said spindles.

2. In an apparatus for tearing and coiling sheet material, means arranged to rotatably support a roll of sheet material, a table arranged to receive the end portion of said sheet material, a cutter mounted for transverse movement across said table whereby the end portion of the sheet material may be cut into a plurality of strips, a plurality of spaced, rotatably mounted spindles,

a feed roller arranged intermediate said spindles to guide the sheet material to said spindles, said feed roller being positioned to produce an angle of substantially 90° between alternate strips of the sheet material, means on each of said spindles for respectively engaging successive strips of said material, and means for simultaneously rotating said spindles whereby the sheet material is torn into lengthwise strips and the strips coiled on the said spindles.

3. In an apparatus for tearing and coiling sheet material, means arranged to rotatably support a roll of sheet material, a table arranged to receive the end portion of said sheet material, a cutter mounted for transverse movement across said table whereby the end portion of the sheet material may be cut into a plurality of strips, a pair of spaced, rotatably mounted spindles, a plurality of reels mounted on each spindle at spaced intervals, the spacing between reels on one spindle corresponding to the location of a reel on the other spindle, means on each of said spindles for respectively engaging successive strips of said material, a feed roller arranged intermediate said spindles to guide the sheet material to said spindles, said feed roller being positioned to produce an angle of substantially 90° between alternate strips of the sheet material, and means for simultaneously rotating said spindles whereby the sheet material is torn into lengthwise strips and the strips coiled on said reels on said spindles.

BERNARD M. PACKTOR.
